UNITED STATES PATENT OFFICE

128,262

DESIGN FOR A COMBINATION MEMO PAD AND PENCIL HOLDER

Mary Lodico, Brooklyn, N. Y.

Application May 31, 1941, Serial No. 101,252

Term of patent 3½ years

To all whom it may concern:

Be it known that I, Mary Lodico, a citizen of the United States, residing at Brooklyn, New York city, in the county of Kings and State of New York, have invented a new, original, and ornamental Design for a Combination Memo Pad and Pencil Holder, of which the following is a specification, reference being made to the accompanying drawings, forming a part thereof.

Fig. 1 is a front view of a combination memo pad and pencil holder embodying my new design; and

Fig. 2 is a central vertical sectional view of the same.

I claim:

The ornamental design for a combination memo pad and pencil holder, substantially as shown.

MARY LODICO.
